UNITED STATES PATENT OFFICE.

OTTO BERGSTROM, OF BRIDGEPORT, CONNECTICUT.

DOOR INDICATOR.

Application filed January 5, 1920. Serial No. 349,538.

To all whom it may concern:

Be it known that I, OTTO BERGSTROM, a subject of Wiborg, Finland, residing at #123 Hope Street, Bridgeport, in the county of Fairfield and State of Connecticut, have invented a new and useful Door Indicator, of which the following is a specification.

This invention relates to certain new and useful improvements in signal apparatus and deals particularly with that type of structure generally applicable to offices, etc., wherein a visual signal is set up to notify the inquiring person whether the occupant of the office is either in or out.

The principal object of the present invention resides in the novel manner whereby I am enabled to give both an audible and a visual signal which may be set to give one or both indications according to the desires of the occupant.

Another object of the present invention is to include in an electric bell circuit a visual signal which may be flashed into view upon closing of the bell ringing switch.

With these and other objects in view it will be apparent to those skilled in the art that certain variations therefrom may be resorted to without sacrificing any of the principles of the present invention and the scope of protection contemplated will appear from the claims.

In the accompanying drawings Fig. 1 is a front elevation of the device as it will appear when in attached position looking from the outside of the door, Fig. 2 is a view of the device as the same will appear from the inside of the door. Fig. 3 is a diagrammatical view of the electric circuit through the various parts of the device. Fig. 4 is a front elevation of the device with the casing removed. Fig. 5 is a side elevation as viewed from the left hand side of Fig. 4. Fig. 6 is a side elevation as viewed from the right hand side of Fig. 4. Fig. 7 is a top view of Fig. 4 with the casing in section and Fig. 8 is a vertical section of the switch button.

Referring more in detail to the drawings wherein similar letters of reference indicate like parts throughout the several views, 1 indicates a base plate upon which the visual

signal and its operating instrumentalities are positioned. Arranged upon this base 1 and secured thereto in any suitable manner is a pair of electromagnetic coils 2, and associated with the active end of the coils is an attractable armature 3. This armature 3 is pivotedly supported at 4' in bracket 4 and on the base 1 and has a light retractile spring 5 arranged to move said armature bar away from the coils when the circuit thereto is broken. Transversely journaled at 7' between upstanding ears 6—7 on the base is a shaft 8, one end of which is provided with a spool or hub portion 9. Vertically journaled at 6' in the upstanding ear 6 is a transversely extending member 10, one end of which is provided with an aperture 11, adapted for reception of a finger 12 on the offset arm 13. This arm 13 may be formed integrally with the armature bar 3 or if desired may be made as a separate element and secured thereto. The opposite end of the member 10 is provided with a downwardly extending arm 14 to which is secured at 14' a flexible pulling element 15 which is wound about the hub 9, and ultimately attached to the free end at 14'' of the downwardly extending end of arm 14. Secured in any suitable manner to the shaft 8 is a segmentally shaped sign 16 which should be transparent, and have imprinted thereon the word "out."

Arranged beneath the transverse shaft 8 and preferably centrally thereof, is an electric light 17. When the circuit is completed in magnetic coils 2 the armature 3 is attracted which moves the offset arm 13 in outward direction causing the arm 10 to move about its pivotal point moving the arm 14 thereof in a downward direction, this arm being connected to the hub 9 by the flexible pulling element 15 will transmit a rotative motion to the shaft 8 and thereby swing the transparent sign into alignment with the light. The base plate 1 has also secured thereto an upstanding bracket indicated at 18 supporting on the outer end thereof a dial 19 having numerals to indicate the hours from one to twelve. A hand 18' is adapted to transverse over this dial and is to be actuated by means of a shaft 19' extending to the rear of the device. All of the structure so

far described is adapted to be arranged upon the outside face of the door and in order to conceal the working parts of the apparatus, a suitable cover indicated at 20 is provided. This cover has cut out portions corresponding to the position of the dial and a rectangular slot at the visual signal. Connecting clips 21-21 are provided at the base plate 1 for the purpose of making proper electrical connection thereto. Also arranged on the face of the door is a switch closing element 22 such as a push button.

Arranged on the rear face of the door for the purposes of giving an audible signal is a vibrating electro magnet the actuations of which are adapted to ring a bell 23. Also arranged on inner face of the door are two switch plugs indicated at 24 and 25 the inner ends of which are pointed as at 26 and adapted to be moved between spring bars 27-27. These switch plugs are adapted for slight reciprocation which when in "out" position allow spring arms to come in contact with the outer end of the plug thereby permitting the circuit to be complete, whereas in the "in" position the spring arms are held apart and rest upon insulated portions of the plug. In order to supply the necessary current for the successful operation of the device any form of battery may be employed.

The circuit being traced as follows: from battery to wire 28 which is connected to one of the contact arms 27 adjacent the button 24, then across the metallic point 26 of button 24 to the opposite contact arm 27 which is connected to one side of the bell by the wire 29, and from the bell the wire 30 is connected to one of the spring arms 27 adjacent the annunciator button 25 and from the arm 27 to the switch 22 by wire 31, through the switch and from the latter to the opposite side of the battery by the wire 32. The complete circuit for the annunciator being as follows when the button 25 is pulled out, from the battery to the wire 28 to the spring contact arm 27 of the bell ringing button 24, from said arm 27 by wire 33 to one side of the annunciator, and from the annunciator through a wire 34 which is connected to one of the spring contact arms 27 adjacent the annunciator button 25, across the metallic point 26 of said button to the opposite spring arm 27, from thence to the battery through the switch 22 by the wires 31 and 32.

A complete operation of the device is as follows: When both plugs 24 and 25 are in the in position as indicated in the diagrammatical sketch, both the bell circuit and audible signal are inactive. When the plug 24 is pulled out it completes the circuit to the bell so that by pushing upon the button 22 the audible signal is given. When both plugs are pulled out the circuit to the bell and also to the visual signal is completed so that by

pressing upon the button 22 both the said signals will be actuated. The coils 2 being energized, will actuate the armature 3 and the arm 13, the movement of the latter will cause the member 10 to be rocked on its pivot and in doing so will pull on the element 15 which in turn will revolve the shaft 8 and swing the indicator 16 so that it may be seen through the opening in the cover. Therefore if the occupant of the room or office desires to vacate for any special length of time he should see that button 25 is pulled out so that the inquiring person by pressing on the button 22 will be notified that the occupant is out. Before leaving, the occupant will also set the dial to indicate the hour that he expects to return. This will also enable the inquiring person to ascertain the time that he can probably see the occupant of the room or office.

What I desire to obtain by Letters of Patent is:

1. A visual signalling device for a door indicator comprising a base plate having ear members, a shaft pivotally mounted in said members, said shaft having a hub at one end thereof, a signal plate connected to said shaft, an electro-magnet on said plate having its axis parallel to the plane of said plate, an armature therefor pivoted on the plate and adapted to swing in a plane parallel to the plane of said plate, and an operative connection between the armature and the hub of the shaft consisting of a member pivoted to one of said ears, one end of said member being connected to the armature and means connecting the other end of said pivoted member with the hub whereby the signal may be actuated upon energization of the electro-magnet.

2. A visual signalling device for a door indicator comprising a base plate having ear members, a shaft pivotally mounted in said members, said shaft having a hub at one end thereof, a signal plate connected to said shaft, an electro-magnet on said plate having its axis parallel to the plane of said plate, an armature therefor pivoted on the plate and adapted to swing in a plane parallel to the plane of said plate, and a transversely extending vertically pivoted bar member, one end of said member being connected to the armature and the other end of said member having flexible means connected to the hub whereby the signal plate may be actuated upon energization of the electro-magnet.

3. A visual signal for a door indicating device having a base plate, an electro-magnet secured to the base plate with its axis parallel to the plane of said plate, an armature for the electro-magnet pivoted on said plate and adapted to swing in a plane parallel to the plane of said plate, a transversely extending shaft pivotally mounted on the

base plate, a signal plate secured to said shaft and a transversely extending bar member pivoted on the base plate at right angles to the shaft and having one of its ends operatively connected to the armature and means connecting its opposite end to the shaft for effecting rotation of the signal plate on its pivot through movement of the transversely extending bar member upon energization of the electro-magnet. 10

In testimony whereof I affix my signature this 3rd day of January, 1920.

OTTO BERGSTROM.
